CLAIM

We claim the ornamental design of a sole for footwear, as shown and described.

DESCRIPTION

FIG. 1 is a side perspective view of a sole for footwear; FIG. 2 is a second side perspective view thereof;

FIG. 3 is a side view thereof;

FIG. 4 is a front view thereof;

FIG. 5 is a second side view thereof;

FIG. 6 is a rear view thereof; and,

FIG. 7 is a top view thereof.

The broken lines showing the remainder of the shoe are for environmental purposes only, and form no part of the claimed design.
